TRUSS FOR A CYCLE SADDLE

Robert C. Persons, ½ Persons-Majestic Mfg. Co.,
72 Commercial St., Worcester, Mass. 01608

Filed Jan. 8, 1970, Ser. No. 20,823

Term of patent 14 years

Int. Cl. D12—14

U.S. Cl. D90—16

FIG. 1

FIG. 2

FIG. 3

FIG. 1 is a view in elevation of a truss for a cycle saddle showing my new design;

FIG. 2 is a bottom plan view looking in the direction of arrow 2 of FIG. 1; and

FIG. 3 is a view in front elevation looking in the direction of arrow 3 in FIG. 1.

The elements shown in broken lines are included for illustrative purposes only.

I claim:

The ornamental design for a truss for a cycle saddle, as shown and described.
